UNITED STATES PATENT OFFICE

JEDDIA B. CLARK, OF DUNKIRK, INDIANA, ASSIGNOR TO THE INDIANA GLASS COMPANY, OF DUNKIRK, INDIANA, A CORPORATION OF INDIANA

DESIGN FOR A SUGAR BOWL OR THE LIKE

Application filed January 6, 1931. Serial No. 38,213. Term of patent 3½ years.

To all whom it may concern:

Be it known that I, JEDDIA B. CLARK, a citizen of the United States and a resident of the city of Dunkirk, in the county of Jay and State of Indiana, have invented a new, original, and ornamental Design for a Sugar Bowl or the Like, of which the following is a specification, reference being had to the accompanying drawing, forming part thereof.

Figure 1 is a perspective view of a sugar bowl or the like, showing my new design;

plane indicated by the line 2—2 of Fig. 1, and

Figure 3 is a horizontal section of my new design taken in the plane indicated by the line 3—3 of Fig. 2, in the direction of the arrows.

I claim:

The ornamental design for a sugar bowl or the like, as shown.

Dated at Dunkirk, State of Indiana, this 23rd day of December, 1930.

JEDDIA B. CLARK.
